UNITED STATES PATENT OFFICE.

WILLARD STRAIGHT, OF NEW YORK, N. Y., ASSIGNOR TO LOUIS D. FROELICK, OF NEW YORK, N. Y.

GAME.

1,281,094.

Specification of Letters Patent.

Patented Oct. 8, 1918.

Application filed October 2, 1916. Serial No. 123,250.

To all whom it may concern:

Be it known that I, WILLARD STRAIGHT, of New York, in the county of New York, and in the State of New York, have invented a 5 certain new and useful Improvement in Games, and do hereby declare that the following is a full, clear, and exact description thereof.

My invention relates particularly to a 10 game designed to interest and amuse players in problems of war.

The object of my invention is to provide a game which is of such a character that it will amuse and educate the players to think 15 about and be interested in problems involved in warfare. A further object is to provide a game which may be played with considerable ease, but which, at the same time, affords a sufficient number of difficulties, and 20 is of a sufficiently varied character to require a considerable degree of skill, so that by playing the game the skill of the player may continually develop. In this way the game is of such a character that it will continue 25 to engage the interest of the players for a long period of time, notwithstanding the fact that the game may have been played a great many times.

While my invention is capable of embodiment in many different forms, for the purpose of illustration I have shown only one form thereof in the accompanying drawings, in which—

Figure 1 is a plan view of a game made 35 in accordance with my invention, and

Fig. 2 is a longitudinal section of the same, taken on line 2—2 of Fig. 1.

In the drawings I have provided a base of fiber or other suitable material, which is 40 divided into two parts, 1 and 2, and which has a covering of felt 3, or other suitable material adapted to retain in position thereon disks 4, with which the game is played. Inasmuch as the covering of felt 3 connects 45 the two parts 1 and 2 together, it acts as a hinge so that the parts 1 and 2 may be readily folded over each other when the game is not in use. In the upper surface of the base there is provided a depression 5 represent- 50 ing a stream of water. Over the stream 5

there is a bridge 6. The features of the game at the two sides of the stream 5 are the same, and one side alone will, therefore, be described in detail. At the side of stream 5 there is an elevation 7 which may be denomi- 55 nated a "hill." On the hill 7 there are located blocks 8 having the representation of wire entanglements thereon which are situated in front of earth works 9, and arranged to be placed in different positions in holes 8^a, 60 according to the skill of the players. Behind the earth works 9 there are trenches 10. In the rear of the trenches 10 there is a representation of a castle with battlements 11, in which there is indicated a gun position 12. 65 At either side of the castle there are further gun positions 13. A road 14 leads from one side of the castle which may represent the entrance thereof to the bridge 6. As representing the entrance to a mine by which 70 the trenches 10 and the castle 11 may be attacked I may provide a slot 15 of just sufficient size to hold one of the disks 4.

In the operation of the game, any number of persons from one to six may play, using 75 the gun positions 12 and 13 as bases from which to discharge disks 4 by pressing upon the edge thereof with other disks of the same character. It will be observed that various obstructions are to be overcome in 80 the playing of the game. For example: The stream 5 is an obstruction, which will stop any one of the disks 4, provided it falls in its course before having crossed the stream. The wire entanglements 8 serve a 85 similar function immediately before the earth works 9. The earth works 9 provide another similar obstruction or hazard. Finally, the battlements 11 provide the supreme obstruction. These various ob- 90 structions protect various positions which are to be reached by the disks 4 when dis- charged in the manner previously described, and the counting will be made according to the place reached and the difficulty encoun- 95 tered in reaching the same. The portion of the ground just beyond the stream 5 will count I; the roadway 14 in front of the wire entanglements 8 will count II; the portion of the field at either side of the castle 11 will 100

count III; the portion of the castle beyond the gun position 12 will count IV; the bridge 6 will count V; the portion of the roadway behind the trenches 10 will count 5 VI; the wire entanglements 8 will count VII; the trenches 10 will count VIII; the gun positions 13 will count IX; the gun position 12 will count X, and the slot 15 representing a tunnel for a mine will count 10 XXV. The persons playing the game will play alternately. If two persons are playing, one will occupy the three gun positions 12 and 13 at one end of the board, and the other person will occupy the three gun positions 15 15 12 and 13 at the other end of the board. If four persons are playing each will occupy one of these same positions, and if six persons are playing each will again occupy one of these several positions. The players may 20 alternate in firing from the opposite sides of the board, and will count according to positions reached by the disk discharged. If, in the course of the game, one of the positions 12 or 13 becomes covered, the player playing 25 from the same cannot count any further until the end of the game. The blocks 8 may be placed in such a position as in the judgment of the player on the two sides will serve as the best protection.

30 When the game is not in use it may be folded and the line on which it is folded is so located that the two battlements 11 will telescope with one another, so that the entire game will occupy as small a position as 35 possible.

While I have described my invention above in detail, I wish it to be understood that many changes may be made therein without departing from the spirit of my 40 invention.

I claim:

1. In a game, a base board having on its surface portions depicting in contour a battlefield and fortifications of such battlefield.
- 45 2. In a game, a base board having its surface shaped to represent in contour the two sides of a battlefield, portions of such surface having the contour of fortifications of such two sides of the battlefield.
- 50 3. In a game, a base board having on its surface portions depicting in contour a battlefield and fortifications of such battlefield, and a base position from which missiles are to be discharged.
- 55 4. In a game, a base board having on its surface opposing portions shaped to represent fortifications of the two sides of a battlefield, and base position from which a missile is to be discharged respectively toward 60 said opposite parts.
5. In a game, a base board having on its surface portions representing, in outline, component parts of a battlefield, and base positions from which a missile is to be dis-

charged, said component parts affording objectives of varying difficulty for said missiles. 65

6. In a game, a base board having on its surface portions representing opposing trenches and base positions from which missiles are to be discharged toward said trenches. 70

7. In a game, a base board having on its surface portions representing opposing trenches and base positions from which missiles are to be discharged toward said trenches, and obstructions located between each of said trenches and the opposing base positions. 75

8. In a game, a base board having on its surface portions representing opposing trenches and base positions from which missiles are to be discharged toward said trenches, and obstructions located between each of said trenches and the opposing base 85 positions, said obstructions being adjustable in position.

9. In a game, a base board having on its surface portions representing opposing trenches and base positions from which missiles are to be discharged toward said trenches, and other component parts of the battlefield disposed adjacent said trenches, and forming objectives of varying difficulty 90 for said missiles. 95

10. In a game, a base board having on its surface a portion shaped to represent a trench and a base position from which missiles are to be discharged toward said trench. 100

11. In a game, a base board having on its surface a portion shaped to represent a trench and a base position from which missiles are to be discharged toward said trench and an obstruction located adjacent 105 said trench.

12. In a game, a base board having on its surface a portion shaped to represent a trench and a base position from which missiles are to be discharged toward said 110 trench and an obstruction located adjacent said trench, said obstruction being movable in position.

13. In a game, a base board having its surface irregularly shaped to provide objectives of varying degrees of difficulty, and a base position from which missiles are to be fired at said objectives. 115

14. In a game, a base board having on its surface portions shaped to represent, in outline, component parts of a battlefield, and base positions from which a missile is to be discharged, said component parts affording objectives of varying difficulty for 120 said missiles.

15. In a game, a base board having on its surface portions shaped to represent opposing trenches and base positions from 125

which missiles are to be discharged toward said trenches, and other component parts of the battlefield disposed adjacent said trenches, and forming objectives of varying 5 difficulty for said missiles.

16. In a game, a base board having its surface irregularly shaped to provide two groups of objectives of varying degrees of difficulty, and base positions from which

missiles are to be fired respectively at said 10 groups of objectives.

In testimony that I claim the foregoing I have hereunto set my hand.

WILLARD STRAIGHT.
